US00D699733S

(12) **United States Design Patent**
Chaudhri(10) **Patent No.:** **US D699,733 S**
(45) **Date of Patent:** **** Feb. 18, 2014**(54) **DISPLAY SCREEN OR PORTION THEREOF
WITH GRAPHICAL USER INTERFACE**(75) Inventor: **Imran Chaudhri**, San Francisco, CA
(US)(73) Assignee: **Apple Inc.**, Cupertino, CA (US)(**) Term: **14 Years**(21) Appl. No.: **29/354,107**(22) Filed: **Jan. 19, 2010****Related U.S. Application Data**

(60) Division of application No. 29/282,840, filed on Jul. 30, 2007, now Pat. No. Des. 628,205, which is a continuation-in-part of application No. 29/281,695, filed on Jun. 28, 2007, now abandoned, which is a division of application No. 29/281,507, filed on Jun. 25, 2007, now Pat. No. Des. 608,366, which is a continuation-in-part of application No. 29/281,460, filed on Jun. 23, 2007, now Pat. No. Des. 604,305.

 U.S. Appl. No. 29/321,374, Chaudhri et al., Graphical User Interfaces for a Display Screen or Portion Thereof, filed Jul. 15, 2008.

(Continued)

Primary Examiner — Melanie H Tung(74) *Attorney, Agent, or Firm* — Sterne, Kessler, Goldstein & Fox P.L.L.C.(57) **CLAIM**

The ornamental design for a display screen or portion thereof with graphical user interface, as shown and described.

DESCRIPTION

The FIGURE is a front view of a display screen or portion thereof with graphical user interface showing my new design. The broken lines showing the display screen and portions of the graphical user interface form no part of the claimed design.

1 Claim, 1 Drawing Sheet(56)
